UNITED STATES PATENT OFFICE.

ARNOLD AUGUST EGLI, OF HAMBURG, GERMANY, ASSIGNOR TO CHOCOLAT TOBLER HOLDING CO., AKTIENGESELLSCHAFT, OF SCHAFFHAUSEN, SWITZERLAND.

METHOD AND APPARATUS FOR THE ALIGNING OF TYPE CARRIERS.

Application filed March 25, 1926, Serial No. 97,302, and in Germany April 2, 1925.

This invention relates to a method and apparatus for the aligning of type carriers assembled to form a line of type especially a justified line of type. The assembling 5 of the type carriers to form a line may be performed in any suitable manner such as by means of a typewriting machine or a type-setting and printing machine or a type-setting and casting machine.

- 10 The invention consists primarily in restricting the movability of the type carriers to a certain extent, aligning the type carriers in their restricted movability and then positively pressing the type carriers together.
- 15 The extent of the restricting of the movability is such, that the aligning of the line formed by the type carriers may be performed without an essentially greater expense of power, while the type carriers are 20 prevented from moving with respect to each other during the following treatment of the line such as justifying; the justifying preferably is performed by shortening the line to the desired length, whereby the primary 25 length of the line is made greater than required by enlarging the distance between each two words and/or between each two type carriers.

A justifying device adapted to perform 30 this method of justifying is more particularly described in Letters Patent 1,608,017 dated November 23, 1926. The method for aligning type carriers assembled to form a line by means of the above mentioned justifying device especially is performed by 35 firstly restricting the movability of the type carriers by shortening the line to a certain extent, then aligning the shortened line and then further shortening the set up line to 40 its definitive length. The word type carriers means carriers of matrices, matrices, type bars with one or more characters and the like. When the type carriers are to be inked with colours by means of inking rollers or the like 45 it is allowable in any case to effect the final inking after the justifying of the line. If an aligning means is employed which is reciprocating at each aligning operation parallel to the direction of the lines the inking 50 mechanism may advantageously follow the spacing means and at least after the final closing of the line may again be guided firmly over the line. The preliminary closing may for example be ensured by pro-

viding yielding tension or compression means 55 in the devices which bring together the closing device to the desired length of line.

Hereby excessive strain or even destroying of the closing device is prevented, which otherwise would occur if for instance more 60 type carriers have been introduced into the device than necessary, so that the set up line is longer than admissible with respect to its later shortening.

The moving of the closing device may be 65 effected by means of a driving wheel adapted to be coupled with a constantly running motor or to be turned otherwise. The driving mechanism for example may be like that described in the pending application 70 Serial No. 628,514, filed March 29, 1923.

The inking roller preferably receives its ink from an ink distributing device as described in the pending application Serial 75 No. 628,514, filed March 29, 1923 for grinding fat colours.

The device according to my invention is able to work in only three phases and in less than one second.

The invention is illustrated by way of 80 example in the accompanying drawings in which:

Figure 1 is a diagrammatic side elevation partially in section of a device according to the invention.

Figure 2 is a plan thereof, and

Figure 3 a view from the left of Figure 2.

Fig. 4 shows a spacing member.

In the drawing A₂ denotes a ratchet wheel which can be coupled to a source of power 90 such as a continuously rotating electric motor and which then rotates in the direction of the arrow shown.

The wheel A₂ is provided with a partially eccentric groove A₆, which is engaged by a 95 projection St of a double armed lever St₁ pivotally mounted in the machine at P. The other end of said lever is shaped in the form of a fork adapted to receive a pin Q on a wheel St₂. This wheel is only toothed on a 100 part of its circumference and adapted to be brought with its toothed part into engagement with the ratchet wheel A₂. On the wheel St₂ an arm St₃ is fastened, which is pivotally connected to a bar St₄. The latter 105 is fastened to a bar St₅ crossing the machine and adapted to be moved in the direction of arrow R. St₁₃ is a rod carrying a series of

small levers St_{14} and engaging a pusher St_6 . H_{12} is a magazine adapted to be moved into different heights and containing a plurality of type-carriers, each provided with a series 5 of characters. The type-carriers preferably are formed by type-bars as shown at Y_{21} (Fig. 1). The magazine also contains the well known spacing members, one of which being shown in Fig. 4 and consisting of a 10 strip of metal a provided with a flat spring b . The flat spring b is fastened at one side of the strip a and only at one of its ends as shown at c . This form of resilient spacing members is well known in the art. The 15 number of the magazines H_{12} , of the pushers St_6 and of the rods St_{13} corresponds to the number of characters, which the line to be printed by means of the machine may have. Y_{23} is a table for bearing the typebars Y_{21} 20 and spacing members, after they have been moved out of the magazines so as to form a line of type.

The above described arrangement is shown and more particularly described in my co-pending application Serial No. 628,514 filed 25 March 29, 1923.

The manner of operation of the aforesaid machinery is as follows:

On each of the rods St_{13} a lever St_{14} is 30 moved into a position according to that of the lever St_{14a} . This is effected by means of the striking of the key in a manner not of importance in connection with the present apparatus and more fully shown and described in Letters Patent 1,466,491 dated 35 August 18, 1923. Now the wheel A_2 is coupled to a source of power (not shown) and rotated in the direction of arrow T (Fig. 1).

Hereby the eccentric portion of the groove A_6 engages the projection St and moves the lever St_1 , so that the wheel St_2 is rotated and is brought into engagement with the teeth of the wheel A_2 . This wheel therefore rotates wheel St_2 and moves the bar St_5 in the direction of arrow R by means of parts St_3 and St_4 . The bar St_5 strikes the moved levers St_{14a} and takes them with it, whereby the pushers St_6 are moved in the same direction. The parts St_7 of each pusher enter the magazines and each move a typebar Y_{21} or a spacing member out of the magazines. The typebars and spacing members rest upon the table Y_{23} and form the line of type. A 55 closing or justifying device Y_1 is arranged on the said table. The justifying device as shown is the same as that described in the Letters Patent 1,608,017 dated November 23, 1926 and is therefore only shown schematically. Y_2 are the movable plates in the interval between each two of which the typebars and spacing members are brought after being moved out of the magazines as above mentioned. Y_3 and Y_4 are the outer of thrust 60 plates and the wedge shaped members Y_5

and Y_6 schematically represent the stepped longitudinal members more fully described in the specification of Letters Patent 1,608,017. These members serve for spacing the plates, Y_2 , which are freely movable, arranged 70 on the table Y_{23} , at a certain distance apart from each other in one direction of movement of the device. The movement of the outer plates Y_3 and Y_4 is effected by means of the apparatus hereinafter described.

On the ratchet wheel A_2 is provided a stop A_{41} which can strike against a rod S_1 , as shown in dotted lines in Fig. 1. The rod S_1 runs in guides and is moved during the further movement of the stop A_{41} in the 80 direction of the arrow shown so far that it assumes the position shown in full lines.

The rod S_1 is provided with teeth which mesh with teeth on a wheel S_9 . The shaft of the toothed wheel S_9 extends transversely through the machine and carries on the other side of the machine, that is to say, on the left hand side looking from the left in Figure 2, a similar toothed wheel not shown with which there meshes a second rod S_{100} 90 provided with teeth. The latter rod also has other teeth which mesh with the teeth on a horizontal toothed wheel S_2 . On the shaft S_3 of this toothed wheel is mounted a crank arm S_4 which is pivoted to a rod S_{51} . This rod S_{51} may be pivoted directly to the member S_6 which runs on guides and is connected with one outer or thrust plate Y_4 of the closing device. In the drawing, Fig. 2 a different constructional form is however 100 illustrated in which the rod S_{51} is hollow. In the hollow rod S_{51} is slidably supported a rod S_{52} which is pivoted to the member S_6 . The rod S_{51} has a collar S_{53} while the rod S_{52} has a pin S_{54} projecting on both sides. Between the members S_{53} and S_{54} is located 105 a spring S_{55} . The member S_6 is provided with teeth which mesh with a toothed wheel S_7 which is journaled in the guiding rail of the member S_6 . On the side opposite to the member S_6 is arranged a rack S_8 which likewise meshes with the toothed wheel S_7 and is rigidly connected with the other thrust or outer plate Y_3 of the closing device.

A_{42} is a stop following the projection A_{41} and is adapted to move the rod S_1 out of the position shown in full lines a certain distance further in the direction of the arrow so that the end of the rod S_1 takes up the position shown in dotted lines. S_{41} is a stop or tooth at the end of a rod S_{10} which has a rack at the other end. This rack meshes with a toothed wheel which is in one piece with the above-mentioned toothed wheel S_9 on the right hand side of the machine or is separate therefrom but mounted on the same shaft.

The method of working of the apparatus is as follows:

By the above-mentioned displacement of 130

the rod S_1 by the stop A_{41} out of the position shown dotted into the position illustrated in full lines the toothed wheels S_9 located on both sides of the machine are rotated and the rod S_1 located on the left hand side of the machine is also moved. This in turn results in rotating the toothed wheel S_7 and with it its crank arm S_4 . This movement takes place in a clockwise direction from the point of view of Figure 2 and has the result that the member S_6 is moved from right to left, and, through the medium of the toothed wheel S_7 , the member S_8 is moved from left to right, that is to say, in the opposite direction. By this means the outer plates Y_3 and Y_4 of the closing device Y_1 , which were previously at the distance from one another denoted by 1 in Figure 2, are moved nearer together to such an extent that the distance between them corresponds to the distance marked 2. The Y_2 plates of the closing device are thus moved nearer to one another and consequently the line formed by the type bars is provisionally justified. In this position of the closing device the type bars are hindered in their free movability in the longitudinal direction and also in the transverse direction in such a way that they can still be displaced relatively to one another by the aligning means Y_{22} which is led away over the line and which engages in grooves in the type bars Y_{21} (Fig. 1) in such a way that the line formed is aligned, but that after this aligning, during the final closing of the closing device which now follows, they can no longer shift relatively to one another. The possibility of the type bars shifting relatively to one another during the aligning by overcoming a certain resistance has the advantage that during the aligning the type bars do not suffer too severely. The resilient connection between the rods S_{51} and S_{52} also renders possible a certain yielding of the closing device.

After the aligning there takes place the complete closing up of the closing device Y_1 , in such a way that the outer or thrust plates Y_3 and Y_4 are brought to the distance 3 from one another. This takes place owing to the further displacement of the rod S_1 , effected by means of the stop A_{42} .

The return movement of the closing device into the position in which the outer plates are at the distance 1 from one another is effected by the stop A_{41} bringing the stop S_{41} out of the position shown in full lines into the lowermost position shown in dotted lines.

This movement results, owing to the rack teeth of the rod S_{10} , in the reversed rotation of the toothed wheel S_9 and of the device associated therewith.

During this movement the plates Y_2 are

spaced at a certain distance apart from each other by means of the members Y_5 , Y_6 as described in Letters Patent 1,608,017 above mentioned.

An inking device F_{12} may follow the aligning means Y_{22} , preferably in such a way that at least during the return of the aligning means, that is to say after the closing device is finally closed, an inking is again effected so that the inking takes place with certainty when the closing device holds the type bars fast in their final position.

The device for moving the aligning means and the inking device in the manner above described is shown in the arrangement which is more fully described in the copending applications Serial Number 628,514 filed March 29, 1923 and Ser. No. 114,783 filed June 9, 1926. The aligning device Y_{22} and the inking device F_{12} are shown to be connected with each other and movably arranged on two guide-rods Y_{24} and Y_{25} . The movement is effected by means of a flexible member F_9 , which is connected to the part Y_{26} surrounding the rod Y_{25} . The ends of the flexible member F_9 (a chain or the like) are wound upon two drums F_8 in opposite directions in such manner that if the drums are rotated in the same sense, the flexible member is wound up by one drum and simultaneously unwound from the other drum. Hereby the flexible member is reciprocated and moves the part Y_{26} to and fro. The drums are fastened on the ends of a rotatable shaft F_{80} , upon which a toothed wheel F_{81} is mounted. F_1 is a disc provided with a cam-groove F_3 and fastened upon a shaft F_{10} crossing the machine. On the other end of the shaft F_{10} a toothed wheel D_2 is mounted which has a shape similar to that described with respect to the aforesaid wheel S_7 , and adapted to be rotated by wheel A_2 in the same manner as wheel S_7 . F_4 is a lever pivoted in the machine at F_5 and carrying a toothed segment F_6 , which engages a toothed wheel F_7 . The wheel F_7 is provided with two rings of teeth, one of them being in engagement with the teeth of the wheel F_{81} . F_2 is a projection or roller arranged upon lever F_4 and engaging the groove F_3 . F_{11} are rollers mounted in the machine in a manner not shown, which guide the flexible member F_9 . The rotation of wheel D_2 imparts a swinging motion to the lever F_4 and effects thereby a similar movement of the shaft F_{80} .

I claim:

1. The art of aligning type carriers, which comprises restricting the movability, aligning the type carriers while so restricted and then locking the carriers after they have been aligned.

2. The art of aligning type carriers, which comprises compressing the type carriers to restrict their movability, aligning the type

carriers while so restricted and then further pressing the carriers together to lock them by shortening the set-up line.

3. In a type setting machine, type carriers forming a line of type, means compressing the carriers to restrict their movability, means for aligning the carriers and means for locking the carriers after they have been aligned.

10 4. In a type-setting machine, type carriers having a straight line of type therein, means to receive the carriers, means to compress the carriers while on said receiving means to frictionally restrain their movability, means 75 to align the carriers while so held and means to operate the compressing means to lock the aligned carriers.

5. In a type-setting machine, type carriers and spacing members cooperating therewith, 20 a pair of closing plates between which the carriers and spacing members are set up, a crank, a connecting rod connected to one plate, means operated by one plate to impart motion in an opposite direction to the 25 other plate, means to rotate said crank a definite distance to close the spacing plates against carriers and spacing members, to restrict their movability, means to align the carriers and means to thereafter additionally 30 rotate said crank to cause said plate to lock the carriers.

6. In a type-setting machine, type carriers, spacing means cooperating therewith, a closing plate cooperating with the type carriers 35 and spacing means set up, a crank, a connecting rod between said crank and plate, means to rotate said crank a definite distance to cause said plate to compress the carriers and spacing members to frictionally restrict the 40 movability of the carriers, means to align the carriers while so held, and means to additionally rotate said crank and thereby cause the plate to move into locking position for locking the carriers and members, and yielding 45 means for said connecting rod to permit it to slightly vary its effective length.

7. In a type-setting machine, carriers for type arranged in a straight line, spacing members for the carriers, a pair of closing 50 plates between which said carriers and members are set up, means operated from one plate to impart equal and opposite motion to the other plate, a crank, a telescoping connecting rod connecting said crank and one 55 of the plates, a spring included between the parts of said connecting rod, means to rotate said crank a definite distance to close the plates against the carriers and spacing members set up to restrict their movability, 60 means to align the carriers so held and means to thereafter additionally move said crank to lock said carriers and members.

8. In a type-setting machine, a table, straight type carriers, and spacing members 65 received on said table, justifying and align-

ing mechanism compressing said carriers and members for aligning and rectifying and locking the carriers and members, said mechanism including a crank and connecting rod, mechanism for partially rotating 70 said crank and then imparting an additional movement, for locking said carriers and members, a toothed wheel, a rack engaging said wheel, a wheel having two stops thereon for successively moving said wheel in its 75 operating movement, a second toothed wheel connected to the first toothed wheel, a rack for said second toothed wheel, a stop on the latter rack arranged in the path of said two stops for returning the first toothed wheel 80 to its initial position.

9. In a type-setting machine, type carriers and spacing members cooperating therewith, closing members between which the carriers and spacing members are set up, means to move said spacing members to compress the set up carriers and spacing members to restrict their movability, means to align the carriers while so held and thereafter lock 85 the carriers and spacing members, and inking means moving in unison with said aligning device.

10. In a type-setting machine, type carriers forming a line of type, resilient spacing members between each two groups of 95 type-carriers forming a word of the line of type, means compressing the carriers to restrict their movability, means for aligning the carriers and means for locking the carriers by shortening the line of type after 100 the carriers have been aligned.

11. In a type-setting machine, type carriers forming a line of type, means for bringing the type-carriers into printing position, spacing members provided with resilient means on a side thereof and adapted to be inserted between each two groups of type carriers forming a word, means for receiving the carriers, means compressing the carriers to restrict their movability, 110 means for aligning the carriers and means for locking the carriers after they have been aligned, the said means for receiving the carriers being adapted to be moved back for spacing the type carriers to definite distances 115 apart from each other.

12. In a device according to claim 3, inking means moving in unison with said aligning device.

13. In a device according to claim 3, an 120 inking device adapted to be moved over the set up line of type, and means for moving the inking device in unison with the said aligning means, said inking device being adapted to follow the said aligning means and to move over the set-up and aligned line after having been justified.

14. In a type-setting machine, type carriers forming a line of type, means compressing the carriers to restrict their mova- 130

- bility, means for aligning the carriers, means for locking the carriers after they have been aligned, a rotatable wheel and two projections on said wheel following one another 5 at a definite distance in the direction of rotation of the wheel, the one projection being adapted to move the means compressing the carriers, the other projection being adapted to move the means for locking the carriers.
- 10 15. In a type-setting machine, type carriers and spacing members co-operating therewith, a pair of closing members between which the carriers and spacing members are set up, means operated by one of 15 the said closing members to impart motion in an opposite direction to the other closing member, means for moving the one closing member a definite distance to close the clos-
- ing members against carriers and spacing members to restrict their movability, means 20 to align the carriers and means to thereafter additionally move the means for moving the one closing member to cause the closing members to lock the carriers.
16. In a device according to claim 3, a 25 yielding member in said means for compressing and locking the carriers.
17. In justifying apparatus for type-setting machines, type carriers, means for restricting the movability of the carriers, 30 means for thereafter aligning the restricted carriers and means for justifying the line after the alignment of the carriers.

In testimony whereof I affix my signature.

ARNOLD AUGUST EGLI,
